UNITED STATES PATENT OFFICE.

EDWARD WELSH, OF BUCKEYE CITY, OHIO.

CRANK.

Application filed March 6, 1922 Serial No. 541,624.

To all whom it may concern:

Be it known that I, EDWARD WELSH, a citizen of the United States, residing at Buckeye City, in the county of Knox and State 5 of Ohio, have invented new and useful Improvements in Cranks, of which the following is a specification.

This invention contemplates the provision of means for rotating or starting an automobile engine or the like, through the instrumentality of a handle which is associated with an engine shaft by a mechanism which permits the handle to be turned in one direction as for the purpose stated, but 10 which prohibits turning of the handle in a reverse direction, thereby obviating injury to the user incident to the reverse rotation of the crank shaft, which is frequently caused by back firing of the engine.

20 The nature and the advantages of the invention will be better understood when the following detailed description is read in connection with the accompanying drawings, the invention residing in the construction, 25 combination and arrangements of parts as claimed.

In the drawings forming part of this application, like numerals of reference indicate similar parts in the several views and 30 wherein:

Figure 1 is a front elevation of the device forming the subject matter of my invention.

Figure 2 is a sectional view taken at a 35 right angle to Figure 1 and showing the device as coupled with an engine shaft.

Figure 3 is a view similar to Figure 1, partly in section.

Figure 4 is a detail view of the ratchet 40 disk.

Figure 5 is a similar view of the rotatable sleeve.

Figure 6 is a sectional view through the sleeve and driving shaft.

45 Figure 7 is a sectional view taken on the line 7—7 of Figure 3.

Figure 8 is a detail view of the stationary plate.

Referring to the drawings in detail, the

device forming the subject matter of this 50 invention essentially embodies an elongated plate indicated at 10 which is adapted to be secured in any suitable manner upon the forward end of a motor vehicle not shown, and in juxtaposition to the crank shaft 11 55 of the motor for said vehicle. The plate 10 is provided with an enlarged central opening 12 for a purpose to be hereinafter described and arranged over this opening is a relatively small plate 13 which is suitably secured to the plate 10. The plate 13 is also provided with a small central opening 14 which receives the spring pressed shaft 15 as shown. Arranged upon one side of the plate 10 is a disk 16 which is associated with said plate for rotation, and this disk is also provided with an enlarged central opening 17, the diameter of which is equal to that of the opening 12 of the said plate 10, and which openings coincide as 60 illustrated. The disk 16 is also provided with peripheral ratchet teeth 18 with which the pawls 19 Figure 3 cooperate to prevent retrograde movement of the disk as will be readily understood. These pawls 19 are arranged at diametrically opposite points, and operate between the end portions of the plate 10 and the relatively small plates 20 which are secured to the end portions of the plate 10 by fastening means 21. In addition to the opening 17, the disk 16 is also provided with an opening 22 which communicates with the opening 17 for a purpose to be presently described.

Arranged in face to face contact with the 85 disk 16, is a second disk indicated at 24, and these disks are secured together to rotate in unison, by means of fastening bolts 25 which are carried by the disk 16 and pass through elongated openings 26 in the 90 disk 24, the bolts having associated therewith nuts 27 to hold the parts operatively associated. The disk 24 is provided with an enlarged central opening to accommodate a sleeve 27', and one end of this sleeve 95 supports a small ratchet wheel 28 of the size to operate within the openings 12 and 17 of the plate 10 and disk 16 respectively. Piv-

oted upon one side of the disk 24 is a pawl 29 which operates in the opening 22 of the disk 16, cooperating with the small ratchet wheel 28 to impart rotation to the sleeve 27 5 incident to the cranking or rotation of the crank shaft in the proper direction to start the engine. It is to be understood that this is accomplished through the instrumentality of a handle 30 which is secured to the 10 disk 24. The shaft 15 above referred to slides through the sleeve 27, the latter being slotted as at 31 to accommodate a cross pin 32 projecting from the opposed sides of the shaft and therefore the rotation of 15 the sleeve is imparted to the shaft 15. One end of the shaft 15 is designed for interlocking association with the adjacent end of the crank shaft 11 in the usual well-known manner, while surrounding the shaft 20 15 and interposed between the adjacent end of the sleeve 27 and a cap 34 supported by the adjacent end of the shaft 15, is a coiled spring 35 which functions to automatically separate the shaft 15 from the crank shaft 25 of the engine as the latter increases its speed subsequent to the starting of the engine as in the ordinary well-known manner.

In practice when it is desired to crank the engine, the shaft 15 is pushed inwardly 30 against the tension of the said springs for interlocking association with the adjacent end of the crank shaft as mentioned. When the shaft 15 is thus arranged the handle 30 is first given a slight turn to the right in 35 order to hold the shaft 15 operatively associated with the crank shaft as will be readily understood. The handle is then subsequently turned in the same direction for the purpose of rotating the crank handle 11, it being 40 above pointed out that as the disks 16 and 24 are thus turned, rotary motion is imparted to the sleeve 27 thru the pawl and ratchet 29 and 28 respectively. The shaft 15 is also rotated and consequently the engine started in the usual manner. It will 45 be noted however that the disks 16 and 24 respectively cannot be rotated in a reverse direction because of the pawls 19 engaging the ratchet teeth of the disk 16, and therefore in event of any reverse rotation of the crank shaft, incident to back firing of the engine, the handle 30 remains stationary and 50 cannot possibly injure the user. During this reverse rotation of the crank shaft under 55 the conditions mentioned, the sleeve 27 and shaft 15 rotate in a similar direction, the ratchet wheel 28 idling past the pawl 29 as the second disk is provided with elongated 60 openings for receiving bolts 25 of the disk 16, thereby any retrograde movement will shift the disk 24 and move the pawl 29 out of engagement with the ratchet 28, by engagement of the pawl 29 against the projection 28 and thus allow the ratchet to revolve 65 with the spring pressed shaft 15. The con-

struction and arrangement of the parts is such, that the engine can be easily and conveniently cranked, without any possibility of injury to the operator incident to the back firing of the engine.

While it is believed that from the foregoing description the nature and advantages of the invention will be readily understood, I desire to have it known that I do not limit myself to what is herein shown and described, and that such changes may be resorted to when desired as fall within the scope of what is claimed.

What is claimed is:

1. A cranking device for engines comprising a stationary member, a pair of disks arranged in face to face contact and mounted on said member for rotation in unison, means for rotating said disks in one direction, means for preventing the rotation of said disks in opposite direction, a shaft slideable through said disks for association with the engine shaft, and means for rotating the first named shaft by said disks, and for permitting reverse rotation of the shaft independently of said disks for the purpose specified.

2. A cranking device for engines comprising a stationary member, a pair of disks arranged in face to face contact and mounted on said member for rotation in unison, ratchet teeth formed on one of said disks, means for turning said disks in one direction, pawls carried by the stationary member and cooperating with said ratchet teeth to prevent rotation of said disks in opposite direction, a shaft slideable through said disks for association with the engine shaft and means for rotating the first mentioned shaft by said disks and allowing reverse rotation of said shaft independently of said disks for the purpose specified.

3. A cranking device for engines comprising a stationary member, a pair of disks arranged in face to face contact and mounted on said member for rotation in unison, means for rotating said disks in one direction, means for preventing rotation of the disks in opposite direction, a sleeve passed through one of said disks, means for rotating the sleeve by said disks, a shaft slideable through said sleeve for association with the engine shaft, means connecting the first mentioned shaft with the sleeve for rotation therewith, and said sleeve and shaft being adapted to rotate in opposite direction independently of said disks for the purpose specified.

4. A cranking device for engines comprising a stationary member, a pair of disks arranged in face to face contact and mounted on said member for rotation in unison, means for turning said disks in one direction, means for preventing rotation of the disks in an opposite direction, a sleeve passed

through one of said disks, a ratchet wheel carried by one end of the sleeve, a pawl carried by said disks and cooperating with said ratchet wheel for rotating the sleeve 5 incident to the rotation of said disks, a shaft slidable through said sleeve for the association with the other shaft, means connect-

ing said shaft with the sleeve for rotation therewith and said pawl and ratchet allowing said sleeve and shaft to rotate in a reverse direction independently of said disks for the purpose specified.

In testimony whereof I affix my signature.

EDWARD WELSH.
